UNITED STATES PATENT OFFICE.

HARRY OSTROVSKY, OF BAYSWATER, LONDON, ENGLAND.

SAFETY-RAZOR.

1,280,824.

Specification of Letters Patent.

Patented Oct. 8, 1918.

Application filed January 26, 1918. Serial No. 213,886.

To all whom it may concern:

Be it known that I, HARRY OSTROVSKY, of Russian nationality, residing at 50 Leinster Gardens, Bayswater, London, England, have invented new and useful Improvements in Safety-Razors, of which the following is a specification.

My invention relates to safety razors with two-edged blades, and it consists essentially in the provision of means for facilitating, and affording four different ways for effecting, the stropping of the blades.

In the accompanying drawing—

Figure 1 is a side elevation of a safety razor constructed according to my invention, the blade being in position for shaving.

Figs. 2 and 3 are end elevations.

Fig. 4 is a central longitudinal vertical section; and

Fig. 5 is a central transverse vertical section of the same.

Fig. 6 is a perspective view of the apparatus without the blade and the guards and lather receptacles.

Fig. 7 is a similar view showing the blade and its clamps or holders detached.

Fig. 8 is a detached perspective view of the guards and lather receptacles.

Fig. 9 is a central transverse vertical section of the safety razor with the blade in one of the stropping positions.

Figs. 10 and 11 are transverse sections illustrating the two other stropping positions of the blade.

Fig. 12 is a perspective view of an alternative form of blade.

In carrying out my invention the blade, which may be an ordinary wafer blade *a*, is rotatably held by a pair of spring arms *b*, *b* carried by the handle or stem *c* of the apparatus, and is clamped in suitable holders *d*, *d* provided with pivots *e*, *e* which are inserted in holes *f*, *f* at the top of the arms *b*.

The guards and the receptacles for the lather constitute an oblong case *g*, open at the top *h* and at one end *i*, so that the handle or stem *c* provided with the arms *b* can be inserted and removed through the said open end, the bottom of the case *g* being slotted at *j* to allow of the passage of the handle or stem which is formed with upper and lower guide grooves *k* and *l* in either of which slide the edges of the slot *j*; *m* is a spring tongue on the bottom of the case *g* having

a stud *n* engaging in a hole *o* or *o'* in the handle or stem *c* in order to lock the two

parts of the apparatus together. The guard-teeth *p* are arranged on the top edge of each side of the oblong case, and the lather collectors consist of ledges *q* at the lower part of the case parallel with the rows of guard-teeth and designed to prevent lather from running down the handle of the apparatus.

The blade is held in either of its proper angular positions with relation to the guard, for shaving and also in proper horizontal stropping position, by means of catches or detents *r*, *r* and in proper vertical stropping position by means of a catch or detent *s*, all designed to be operated by the hand against the action of a spring *t* as follows—

The catches or detents *r* and *s* are carried by a plate *u* mounted on a square spindle *v* arranged to slide and turn in the spring arms *b*, *b* so that when the said spindle is pushed by means of its knob *w* against the action of the spring *t* the plate *u* will be moved away from one of the spring arms *b* and will carry it with the detents clear of the blade *a*. When, however, the knob *w* is released, the detents *r* can be caused to hold the blade in one or other of the shaving positions as in Figs. 1, 2, 3 and 5, or in the horizontal stropping position as in Fig. 10; or the detents may be held out of action to permit certain parts to limit the rocking movement of the blade when stropping in the manner hereinafter explained with reference to Fig. 11. Or the detent *s* which passes through a hole in the spring arm and is formed with a cut or groove as shown, can be caused to hold the blade in the vertical stropping position as in Fig. 9.

When it is required to strop the blade the oblong case *g* may be removed from the handle *c* carrying the arms *b* and blade *a*, and the two edges of the latter stropped successively, and the stropping can be effected either with the blade turned into the vertical position or into the horizontal position.

It is of advantage, however, when stropping with the blade in the vertical position, to apply the oblong case *g* to the handle or stem in the lower position as shown in Fig. 9, that is to say, with the edges of the slot in the guide grooves *l* instead of in the guide grooves *k*, because the guard-teeth *p* will then be found to give the proper stropping angle as represented by the dotted line *y'* which indicates the strop.

Fig. 10 shows the blade in the horizontal stropping position.

To enable the blade to be effectively stropped by the most inexperienced person 5 rollers α , α are provided between which and the blade a the strop y' is introduced as shown in Fig. 11 and held taut with one hand while the razor is moved to and fro with the other hand.

10 The rollers α are mounted in the arms b in such a manner that they can when required be readily brought into and secured in, the proper stropping proximity to the blade and withdrawn therefrom when the 15 stropping has been completed.

To this end the rollers α are advantageously pivoted eccentrically as shown within the spring arms b by mounting them in a three-sided frame y , arranged to turn with 20 the spindle v which can also slide therein so that by thus turning the frame the rollers are caused to approach or recede from the blade. To this end the spindle v is made square at parts co-acting with the frame y 25 but is of circular section where it engages the arms b . The rollers α are locked in their raised position, shown in Fig. 11, by means of the catch or detent s and in their lowered position by means of the catch or detent z 30 on the plate u , both the said catches or detents passing through holes in one of the spring arms b and engaging in a cavity or depression in one end of the frame y .

The extent to which the blade can alternately rock in order to give it the proper stropping angle, is limited by the ends of 35 the frame y , the catches or detents r , r being meanwhile held out of contact with the blade by reason of the catch or detent s being arrested on its return passage through 40 a hole in the spring arm b by the bottom of the cavity or depression in the end of the frame y .

When it is desired to strop the blade, as 45 illustrated in Fig. 11, the handle of the razor is moved down the strop y' and this causes the upper edge of the blade to engage the strop. As the blade moves down, the friction exerted on the curved surface 50 of the lower holder d will have a tendency to bring the lower edge of the blade into contact with the strop, but this is prevented by the curved surface of the lower holder d engaging the left hand upper edge of the 55 frame y . As the razor moves down the strop, the left hand roller α will engage the under surface of the strop but when the razor is moved up the strop, the right hand roller α will be brought into engagement 60 with the strop and the blade will be rocked, so that its lower edge will be brought into contact with the strop and the upper portion of the curved surface of the lower holder d will be brought into engagement 65 with the right hand upper edge of the frame

y . It will be seen that no matter whether the razor is being moved in one direction or the other, the proper edge will be held in engagement with the strop through the curved under surface of the lower holder 70 d engaging the upper edge of the frame y .

Instead of a pair of rollers α , α a single roller, rod or plate can be employed, and, instead of the wafer blade a clamped in the holders d , d I can employ a blade in one 75 piece resembling two hollow ground razors placed back to back, as shown in Fig. 12.

Claims:

1. In a safety razor with a two-edged blade, a blade holder mounted upon a handle, a case adapted to removably receive the said holder and handle, guard-teeth upon the top edge of each side of the case and ledges at the lower part of the case parallel with the rows of guard-teeth and designed to receive the lather and prevent it from running down the handle. 80

2. In a safety razor with a two-edged blade, the combination of a case having two rows of guard teeth and lather collecting 90 ledges, of a pair of spring arms, and a holder for the blade provided with means co-operating with said arms for pivotally supporting said blade.

3. In a safety razor with a two-edged 95 blade, a case having two rows of guard-teeth and lather collecting ledges, a pair of arms pivotally holding the blade and mounted on a stem or handle, a slot in the bottom of the 100 said case, a groove in the said stem to receive the edges of the slot, a recess or hole in the said stem above the groove, and a spring tongue on the bottom of the case engaging the said recess or hole.

4. In a safety razor with a two-edged 105 blade, a case having two rows of guard-teeth and lather collecting ledges, a pair of arms pivotally holding the blade and mounted on a stem or handle, a slot in the bottom of the 110 said case, upper and lower grooves in the said stem, both of which are designed to receive the edges of the slot, a shoulder in the said stem above each groove, and a spring tongue on the bottom of the case 115 engaging either shoulder.

5. In a safety razor with a two-edged blade pivotally supported within a pair of arms, means for holding the blade in either of two proper angular positions for shaving, and also in proper horizontal stropping position 120 comprising a plate mounted on a spindle arranged to slide and turn in the said arms, catches or detents on the said plate adapted to engage the blade, and an actuating knob and a spring on the said spindle. 125

6. In a safety razor with a two-edged blade pivotally supported within a pair of arms, means for holding the blade in a proper vertical stropping position comprising a 130 plate mounted on a spindle arranged to slide

and turn in the said arms, a catch or detent on the said plate having a cut or groove adapted to engage and hold the blade, a hole in one of the said arms for the passage 5 therethrough of the catch or detent and an actuating knob and a spring on the said spindle.

7. In a safety razor with a two-edged blade pivotally supported within a pair of arms, 10 rollers mounted in the said arms in such a manner that they can be readily brought into, and secured in, proper stropping proximity to the blade, and withdrawn therefrom when the stropping has been completed.

8. In a safety razor with a two-edged blade pivotally supported within a pair of arms, rollers mounted in a three-sided frame arranged to turn with a spindle rotatably supported in the said arms, the said rollers being eccentrically disposed with relation to the said spindle which is also capable of sliding in the said frame.

9. In a safety razor with a two-edged blade

pivots supported within a pair of arms, 25 a three-sided frame mounted below the blade in the said arms on a spindle arranged to turn with the said frame and also slide therein, rollers carried by the said frame and eccentrically disposed with relation to 30 the said spindle, a plate mounted on the said spindle which is also arranged to slide and turn in the said arms, catches on the plate, holes in the said arms for the passage therethrough of the catches, a cavity in one 35 end of the said frame for the reception of the catches, and an actuating knob and a spring on the said spindle.

10. A safety-razor comprising a holder provided with parallel arms, a double edged 40 blade pivotally supported by said arms, guard teeth carried by said holder, two catches for holding said blade in either of two proper angular positions for shaving, and also in proper horizontal position for 45 stropping, and another catch for holding said blade in vertical position for stropping.

HARRY OSTROVSKY.
